CLAIM

The ornamental design for an electrical card connector, as shown and described.

DESCRIPTION

FIG. 1 is a front, top and right side perspective view of an electrical card connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front, top and right side perspective view thereof, in use condition.

The broken line showing is for illustrative purposes only and forms no part of the claimed design.
